UNITED STATES PATENT OFFICE.

CARL H. NORDELL, OF FORT WAYNE, INDIANA, ASSIGNOR TO WAYNE TANK & PUMP COMPANY, OF FORT WAYNE, INDIANA, A CORPORATION OF INDIANA.

CONTROL VALVE.

Application filed July 20, 1922. Serial No. 578,247.

To all whom it may concern:

Be it known that I, CARL H. NORDELL, a citizen of the United States, residing at Fort Wayne, in the county of Allen and State of Indiana, have invented new and useful Improvements in Control Valves, of which the following is a specification.

My invention relates to control valves adapted to secure a regulated intermittent withdrawal of liquid from a container; as for instance apparatus for the continuous softening of water by the use of hydrated alumina silicates, generally popularly known as zeolites.

Such apparatuses for the continuous softening of water are shown in my co-pending applications; one filed July 25th, 1921, Serial No. 487,465, and one filed May 15, 1922, Serial No. 561,095; each of which shows a control valve of a generally similar form.

The purpose of the invention is to intermittently, but at substantially equally spaced intervals, withdraw liquid in substantially equal charges from a receptacle in which the liquid is under pressure. In a water softening apparatus the receptacle from which the liquid is withdrawn is the zeolite washing chamber.

This control valve can always be used to withdraw liquid from a receptacle under higher pressure than that into which the outlet discharges; even if the pressure in the first receptacle is merely atmospheric providing that of the second is then below atmospheric pressure.

In the particular embodiment of my invention selected for illustration,

Fig. 1 is a vertical axial section of the control valve of a zeolite water softening apparatus and attendant parts with the valve open,

Fig. 2 a detail, is a perspective view of the poppet slug,

Fig. 3 a detail, is a perspective view of the ring slug, and

Fig. 4 is the same as Fig. 1, but with the valve closed, the ring slug being in mid position, as it is falling.

Referring now to the drawings, 1 represents the valve housing, 2, a sediment chamber into which the liquid (spent brine from the zeolite washing chamber not shown),

flows through the pipe 3 and thence upwardly through the opening 4 forcing the

poppet slug 5 and the ring slug 6 (which two in combination form a rather loose fitting piston in the tube 7) until the apex 8 of the slug strikes the pusher pin 9, seated axially so as to afford limited vertical movement of the pusher pin in the hole 10 bored to receive it in the valve housing 1.

The rising piston 5-6 forces the water above it in the chamber 11 through the opening 12 in the pusher pin into the chamber 13 forcing upwardly the flexible diaphragm 14 and the weight 15 seated thereon. The outlet 16, which is always open, is arranged to require a predetermined longer time to let out the water in the chamber 13 than is required to let it in through the opening 12 in the pusher pin 9. This differential allows the seated piston to be raised by the force of the water until the slug 5 pushes up the pusher pin 9 and seats itself against the seat 17, preferably resilient, on the under side of the housing 1. The poppet slug 5 closes the opening 10 between the chambers 11 and 13 and stops the upward flow of liquid; whereupon the ring slug 6 immediately falls to the position shown in Figure 1 by gravity. A stud, 18, passes through the diaphragm 14 and is secured to the weight 15 above, while below it has a shoulder 19 against which a spring 20 rests and to which said spring is secured. The lower end of this spring seats upon the top of the pusher pin 9 to insure that the poppet slug will be thrown clear of its seat when unseated by the descending weight 15.

The closing of the opening 10 between the chambers 11 and 13 stops the flow of liquid into the sediment chamber 2. The valve housing 1 and its cap 21 have lateral circumferential flanges 22 and 23 respectively, between which rests the diaphragm 14 which is held securely in position by the stud bolts 24 and lock nuts 25. These bolts are produced upwardly forming guides for the weight 15. A slug receptacle 26 acts as a partial closure for the top of the sediment chamber 2 and as a seat for the bottom of the tube 7. A packing washer 27 is provided upon which the lower end of the tube 7 seats. The slug receptacle 26 and the valve housing 1 are held securely in position by the tie rods 33.

The slug 6 has an annular recess 28 concentric with the axial opening 29. An an-

nular boss 30 on the lower end of the poppet slug 5 is adapted to seat in the annular recess 28 giving a dash pot effect, providing against shock when the poppet slug 5 falls 5 when unseated by the downward pressure of the pusher pin 9.

When the valve 5—6 has seated, the diaphragm stops rising and as the water discharged through the outlet 16 and the 10 weighted diaphragm gradually descends, the spring 20, fixed to the shoulder 19, presses on the pusher pin 9 with sufficient force to dislodge the slug 5 from its seat, allowing water to flow around the slug 5, whereupon 15 it falls into contact with the ring slug 6, sealing off the opening 29 in the ring slug so that elements 5 and 6 in combination form a piston and will rise together as hereinbefore described. While the slug 5 is falling, 20 the liquid below it flows past it into the chamber 11. The cock 31 is provided to draw off sediment from the apparatus.

The effective size of the opening 16 may be regulated by a manually operated cock 25 32 or by a mechanically operated valve.

Obviously many changes can be made in the device without departing from the spirit of this invention. I do not limit myself to the apparatus herein illustrated and described, but conceive as within the scope of my invention any control valve readable upon the claims or any of them, that may be ultimately allowed hereon.

I claim as my invention and desire to secure by Letters Patent of the United States:—

1. A control valve having a piston formed of a plurality of parts which automatically engage to co-act and constitute an effective piston and then automatically disengage.

2. In combination with a control valve of the piston type, a piston consisting of two elements, which automatically engage to co-act and constitute an effective piston and then automatically disengage.

3. A control valve comprising a cylinder connected by a member having a passage to a chamber, a plurality of parts within said cylinder which when co-acting form an effective piston adapted to deliver substantially accurately measured charges of liquid to said chamber and then close said passage between said cylinder and said chamber and means for automatically reopening said passage to allow the co-acting parts in the cylinder to deliver another charge to the chamber, said cycle of events being continuously and automatically maintained.

4. A control valve for withdrawing liquid in substantially uniform charges having in combination a cylinder, a chamber and a liquid connection from said cylinder to said chamber, a piston in said cylinder formed of a plurality of parts which under the pressure of inflowing liquid co-act to form an effective piston adapted to deliver a substantially accurately measured charge of liquid from said cylinder to said chamber, one of said piston parts adapted in extreme raised position to close said connection whereupon the other piston part or parts fall by gravity to the bottom of the cylinder, means for allowing the liquid to escape from said chamber more slowly than it enters thru said connection and means within said chamber for unseating said connection closing piston part upon the escape of a predetermined quantity of liquid from said chamber, whereupon said connection closing piston part falls by gravity into co-acting contact with the other piston part or parts.

5. A control valve for withdrawing liquid in substantially uniform charges, having in combination a cylinder, a chamber and a liquid connection from said cylinder to said chamber, a piston in said cylinder formed of a plurality of parts which under the pressure of inflowing liquid co-act to form an effective piston adapted to deliver a substantially accurately measured charge of liquid from said cylinder to said chamber, one of said piston parts adapted in extreme raised position to close said connection whereupon the other part or parts fall by gravity to the bottom of the cylinder, means for allowing the liquid to escape said chamber more slowly than it enters thru said connection, a diaphragm within said chamber adapted to be flexed upwardly by the liquid forced thru said connection into said chamber; a plunger, with a longitudinal liquid passage reciprocable in said connection, means for depressing said diaphragm and means for forcing said plunger downwardly to unseat said connection closing piston part when said diaphragm has been depressed whereupon said connection closing piston part falls by gravity into co-acting contact with the other piston part or parts.

In testimony whereof I have hereunto set my hand in presence of two subscribing witnesses.

CARL H. NORDELL.
